UNITED STATES PATENT OFFICE

91,750

DESIGN FOR A GLASS BOTTLE

David Shanks Anderson, Glasgow, Scotland, assignee to Scotia Distillers Limited, Glasgow, Scotland, a British company

Application November 8, 1933, Serial No. 49,672

Term of patent 14 years

To all whom it may concern:

Be it known that I, DAVID SHANKS ANDERSON, a subject of the United Kingdom of Great Britain, and a resident of Glasgow, Scotland, whose post-office address is Dawson House, 266 Clyde Street, Glasgow, C. 1, have invented a new, original, and ornamental Design for a Glass Bottle, of which the following is a specification, reference being had to the accompanying drawing, forming part thereof.

Fig. 1 is a perspective view and Fig. 2 is a plan view of the bottle showing my new design.

I claim:—

The ornamental design for a glass bottle as shown.

In testimony whereof I affix my signature in presence of two witnesses.

DAVID SHANKS ANDERSON.
